UNITED STATES PATENT OFFICE.

JAMES A. BLAKE, OF CAMBRIDGE, MASSACHUSETTS, ASSIGNOR TO RAISED PROCESS MACHINE COMPANY, OF BOSTON, MASSACHUSETTS, A CORPORATION OF MASSACHUSETTS.

RAISED-PRINTING APPARATUS.

Application filed July 22, 1924. Serial No. 727,578.

To all whom it may concern:

Be it known that I, JAMES A. BLAKE, a citizen of the United States, residing at Cambridge, county of Middlesex, State of Massachusetts, have invented a certain new and useful Improvement in Raised-Printing Apparatus, of which the following is a specification, reference being had therein to the accompanying drawings.

10 The invention relates to an improvement in apparatus for producing raised printing having an appearance somewhat like embossing and engraving by first printing the design or other matter upon the sheet, card or other article with ink or other suitable substance and then while the printing substance is still in green state dusting thereon a fusible powder, then passing the article through a suitable heating device to cause 20 the powder to melt and to amalgamate with the heating substance, then cooling and drying it so as to harden it.

The present invention relates especially to the oven through which the printed article 25 is caused to travel for the purpose of amalgamating the printing substance and the fusible substance. One drawback to the apparatus heretofore used for this purpose has been the difficulty of getting a proper 30 amount of oxygen for the gas burner without undue loss of heat.

One object of the present invention is to construct the oven in such a manner as to provide an ample supply of oxygen and yet 35 conserve the heat. Another object is to construct the apparatus so as to obtain the above mentioned conservation of heat and proper amount of oxygen and at the same time have the apparatus in compact form.

40 The invention will be fully understood from the following description when taken in connection with the accompanying drawings, and the novel features thereof will be pointed out and clearly defined in the claims 45 at the close of this specification.

In the drawings:

Fig. 1 is a view in elevation of the apparatus embodying the invention, the machine being partly broken away to simplify the 50 illustration.

Fig. 2 is a plan view of the apparatus shown in Fig. 1.

Fig. 3 is a section taken on line 3—3, Fig. 2.

Fig. 4 is a section taken on line 4—4, 55 Fig. 3.

Referring now to the drawings:

There is shown at 10 an outer casing having an oven in the form of an inverted box which is open at the bottom and closed at 60 the top, sides and ends, the lower edge of each end member having a passway 11 for the passage of the upper run of the carrier 12. The said casing is mounted on suitable 65 supports. As shown in the drawings, it is supported as follows: The lower edges of 70 the side walls of the casing are each formed with an inturned flange 13 which rests on the upper, horizontal flange 15 of a plurality of angle plates 14 whose vertical portions are bolted to the upright flanges 16 of the angle bars 17 which extend lengthwise of the casing and are supported by the frame 75 of the machine having legs 18. Preferably the casing 10 is made of sheet metal having an asbestos lining 19.

Preferably the said outer casing has a double top formed by an outer top 20 and an inner partition 21 forming an enclosed air space 22 between the top member 20 and the 80 partition member 21 to retard the radiation of heat.

A bottom plate member 23 is provided which I term a reflector extending across the lower part of the outer casing and mounted 85 on angle plates 24 which rest on the flanges 17 at a short distance below the open bottom of the casing 10. This reflector is of somewhat less area than the cross sectional dimensions of the casing so that there is a 90 marginal open space 25.

An inner casing or oven 26 is provided having top, side and end walls but open at the bottom. This inner casing is preferably 95 supported, as shown, by brackets consisting of angle plates 28 having flanges which are respectively bolted or otherwise fastened to the upright side walls of the inner and outer casings. The said inner casing or oven is 100 preferably made of sheet metal and formed with inturned flanges 31 around its lower edge although the flanges are not essential.

The horizontal bottom flanges 13 of the outer casing are formed with a series of apertures 29 and the top of the inner casing 105 is formed with a plurality of apertures 30 so that there is free circulation of air through the apertures 29 in the bottom

flange 13 of the outer casing and through the marginal spaces 25 at the sides of the reflector so that air will pass into the lower part of the outer casing through the open spaces 25, thence around the sides of the conveyor 12 to be hereinafter described as well as through the apertures in the mesh work of said conveyor into the inner casing 26 where it is heated, thence up through the apertures 30 in the top of the inner casing into the air space between the top of the inner casing and the partition member 21 of the outer casing, thence down through the air spaces between the sides of the inner and outer casing and out through the apertures 29. It is immaterial whether the air currents follow the course above described or follow some other course, the essential feature being that there shall be free circulation of air from outside into the oven and thence to the space between the top walls of the inner casing and the outer casing and thence to the outer air again.

The conveyor 12 for the printed sheets or cards or other articles runs longitudinally through the lower part of the outer casing 10 and beneath the oven or inner casing 26. This conveyor is preferably of wire mesh in the form of an endless traveler, the upper run of which passes through the entrance and exit passages 11, 11 at the two ends of the outer casing. The conveyor runs over suitable rolls 33, 34 at the ends of the machine, said rolls being driven by any suitable mechanism. As shown in the drawings, the forward roll 34 is driven by the motor 36 by means of intermediate mechanism consisting of a worm 37 on the motor shaft 38, worm gear 39 on the shaft 40 which carries a bevel gear 41 and a bevel gear 42 on the shaft 44 which carries the roll 34. Any other suitable driving means may be employed.

A suitable heating means is mounted with, in the inner casing 26. In the form shown in the drawings the heating medium consists of a gas burner 45 having at one end a lug 46 which is mounted in one of the end walls of the inner casing 26 and having at its other end a tubular extension 47 which passes through the opposite end wall of the inner casing and through the end wall of the outer casing. The said tubular extension 47 is connected with a suitable gas supply pipe having a valve 48 to control the admission of gas to the burner. The burner is provided with burner orifices 49, preferably in its underside so that the flame will be projected downward and throw the heat against the upper run of the conveyor 12 and the printed sheets of cards riding on the upper side of the carrier.

The cards are printed by any suitable mechanism and while the ink is still green they should be dusted with a suitable fusible

powder which will adhere to the moist and sticky ink, and the surplus powder removed by shaking or blowing it off, then the printed and dusted articles are placed on a part of the conveyor which is about to enter the oven casing. The speed of the conveyor and the degree of heat should be so regulated that the fusible substance will be fused during the travel through the oven and the articles may be removed at the outlet end in any suitable manner. As shown in the drawings there is provided a chute 51 onto which the articles drop from the carrier when it makes the turn after going over the roller 34.

The reflector 23 which is below the upper run of the conveyor will check the escape of the heated air through the open bottom of the oven on the under side of the reticulated carrier, and will also act as a reflector to reflect it upwardly.

By reason of its ventilated inner casing 26 sufficient draft and oxygen are provided to keep the flame alive and produce the necessary heat, and the closed top and sides of the outer casing prevent the unnecessary escape of the heat, thus conserving the heat. Moreover, the apparatus may be very compact as the requisite heat may be obtained in a very short oven.

What I claim is:

1. In an apparatus for producing raised printing, two hollow casings, one surrounding the other, each having a top and sides and an open bottom, said casings being spaced to form an air space between their walls at the top and sides, a heating medium in the inner casing, the top wall of the inner casing being provided with air ports to permit the heated air to pass from the interior of the inner casing into the space between the top walls of the two casings, and thence down between the adjacent side walls of the two casings to the outside air, and a conveyor for the printed articles which travels through the lower part of the outer casing.

2. In an apparatus for producing raised printing, two hollow casings, one surrounding the other, each having a top and sides and an open bottom, said casings being spaced to form an air space between their walls at the top and sides, a heating medium in the inner casing, the top wall of the inner casing being provided with air ports to permit the heated air to pass from the interior of the inner casing into the space between the walls of the two casings, and thence down between the adjacent side walls of the two casings to the outside air, and a conveyor for the printed articles which travels through the lower part of the outer casing beneath the heating medium.

3. In an apparatus for producing raised printing, an inner casing having a top, sides

and an open bottom, a heating medium mounted therein, an outer casing surrounding the top and sides of said inner casing, and having sides, a closed top and an open bottom, said casings being spaced to form air spaces between their walls, the top wall of the inner casing being formed with air ports to permit the heated air to pass from the interior of the inner casing into the top space between the casings, and thence down through the space between the side walls of the two casings to the outside air, a conveyor for the printed articles which travels through the lower part of the casings and a heat reflecting member below the path traversed by the articles carried by the conveyor.

4. In an apparatus for producing raised printing, an oven having an open bottom, a heating medium mounted therein, a casing surrounding the top and sides of said oven, and having an open bottom, said oven and casing being spaced to form air spaces between their walls at top and sides, the open bottoms of the oven and casing providing communication from the outer air into the oven, the top wall of the oven being formed with a plurality of apertures which provide passages for the heated air from the oven into the air space between the top of the oven and casing and thence into the spaces between the side walls of the oven and casing, a conveyor for the printed articles which travels through the lower part of the casing and a heat reflecting member below the path traversed by the articles carried by the conveyor, said reflector partially closing the bottom of the oven in such manner as to leave air passages around the sides of said reflector into the oven and into the space between the oven and the casing.

5. In an apparatus for producing raised printing, an oven having an open bottom, a heating medium mounted therein, a casing surrounding the top and sides of said oven, and having an open bottom, said oven and casing being spaced to form air spaces between their walls at top and sides, the open bottoms of the oven and casing providing communication from the outer air into the oven, the top wall of the oven being formed with a plurality of apertures which provide passages for the heated air from the oven into the air space between the top of the oven and casing and thence into the spaces between the side walls of the oven and casing, a conveyor for the printed articles which travels through the lower part of the casing and a heat reflecting member below the path traversed by the articles carried by the conveyor, said reflector partially closing the bottom of the oven in such manner as to leave air passages around the sides of said reflector into the oven and into the space between the oven and the casing, said heat-

ing medium being constructed and arranged to direct the heat downward toward the conveyor.

6. In an apparatus for producing raised printing, an inner casing having a top, sides and an open bottom, a heating medium mounted therein, an outer casing surrounding the top and sides of said inner casing and having a closed top and open bottom, said casings being spaced to form air spaces between their walls at the top and sides, the top wall of the inner casing being formed with air ports to permit the heated air to pass from the interior of the inner casing into the top space between the two casings and thence down through the space between the side walls of the two casings, the outer casing extending down below the inner casing, each side wall of said outer casing having an inwardly extending flange at its lower part formed with apertures for the passage of air and a conveyor for the printed articles which travels through the lower part of the casing beneath the heating medium.

7. In an apparatus for producing raised printing, an inner casing having a top, sides and an open bottom, a heating medium mounted therein, an outer casing surrounding the top and sides of said inner casing and having a closed top and open bottom, said casings being spaced to form air spaces between their walls at the top and sides, the top wall of the inner casing being formed with air ports to permit the heated air to pass from the interior of the inner casing into the top space between the two casings and thence down through the space between the side walls of the two casings, the outer casing extending down below the inner casing, each side wall of said outer casing having an inwardly extending flange at its lower part formed with apertures for the passage of air, a conveyor for the printed articles which travels through the lower part of the casing beneath the heating medium, and a heat reflecting plate in the lower part of the outer casing beneath that portion of the conveyor which carries the printed articles, said heat reflecting plate being of smaller dimension than said outer casing whereby passages are left around the margin of said reflecting plate.

8. In an apparatus for producing raised printing, an inner casing and an enclosing casing each having a closed top and sides and being open at the bottom, said casings being spaced to form air spaces between their walls at the top and sides, a heating medium within the inner casing, a conveyor for the articles which travels underneath the heating medium and is exposed to the heat therefrom and a heat reflecting plate beneath the path of travel of the articles on the conveyor, the casings being constructed

4
to provide passages for outside air from beneath up into the inner casing, the top of the inner casing having outlet ports for the heated air to pass into the space between the tops of the two casings whence it passes down through the space between the side walls, the outer casing being formed with outlet passages at the lower part thereof.

9. In an apparatus for producing raised printing, an inner casing and an enclosing casing each having a closed top and sides and being open at the bottom, said casings being spaced to form air spaces between their walls at the top and sides, a heating medium comprising a gas burner within the inner casing, a conveyor for the articles

which travels underneath the heating medium, said gas burner having burner orifices which direct the flame downward toward the conveyor, and a heat reflecting plate beneath the path of travel of the articles on the conveyor, the casings being constructed to provide passages for the outside air from beneath up into the inner casing, the top of the inner casing having outlet ports for the heated air to pass into the space between the tops of the two casings whence it passes down through the space between the side walls, the outer casing being formed with outlet passages at the lower part thereof. 20 25 30

In testimony whereof I affix my signature.
JAMES A. BLAKE.
